UNITED STATES PATENT OFFICE.

JOHN E. OSTLINE, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed May 8, 1924. Serial No. 711,782.

This invention relates to telephone systems in general, but more particularly to telephone systems using manual switchboards and in which automatic switches are employed for 5 extending or distributing calls to the operators. Generally stated, the object of the invention is to provide an improved and highly efficient call or traffic distributing system.

Special objects of the invention are the 10 provision in a system of this character of new and improved circuit arrangements whereby the calling party after hanging up always secures a connection to an idle operator for the next call regardless of whether 15 the previous connection to the called line has been taken down or not; whereby the called party can originate a call to an idle operator immediately after he and the calling party have hung up and before the previous connection is taken down; whereby the sleeves 20 of both the calling and called party's multiple jacks will test non-busy to calls for these lines immediately after the calling and called parties have hung up and before the connection 25 has been taken down; whereby the operator instantly receives a guard tone upon failure to properly depress the ringing master key at the time of inserting the plug in the multiple jack of the called line; whereby 30 the operator can clear a permanent, that is, a grounded or short circuited line, out of her position by momentarily operating a key, which will at the same time signal the switchboard attendant and place a trouble tone on 35 the multiple jack sleeve of the defective line; and whereby separate peg counts are obtained automatically of calls completed in the multiple and those not completed.

In a system characterized by the invention, 40 a subscriber whose line is arranged for single or four party jack per line service and which terminates in an individual line switch and multiple jack, makes a call in the following manner: He takes down his receiver and the 45 individual line switch automatically seizes for him a preselected trunk leading to an operator's open position. Common position equipment will mark and store the call and light a pilot lamp on the operator's key shelf 50 to indicate the number of calls stored. The subscriber upon being connected with the trunk receives a tone indicating this fact. The common position marking and storing equipment automatically connects the trunk

to the operator's telephone circuit in the same order as the call was originated in relation to other calls. This will light a common call lamp on the operator's key shelf to indicate that a trunk is connected to her set. In case of a restricted line making a call, a restricted 55 service lamp will also light, thereby giving the operator positive indication as to the kind of service to be allowed. The tone given to the subscriber also stops, thereby giving him positive indication that the operator is 60 ready to take his number. After the desired number has been obtained by the operator, she selects any cord circuit on her position and tests the line wanted for the busy or out-of-order tone. If the line called is not busy 65 or out of order, the operator inserts the plug in the multiple jack of this line and depresses momentarily the common frequency key corresponding to the party desired on the line. This starts the automatic ringing of the 70 wanted party's bell, causes a finder switch to connect the cord with the trunk in use, and causes the next call to be automatically connected to the operator's set. If the line called is busy the operator momentarily 75 depresses the common busy key, without inserting the plug in any jack, and this will place a busy tone on the calling party's line until he hangs up, and the next call is automatically connected to the operator's set. If the party called is on the same line as the 80 calling party the operator will get a reverting tone when testing for busy, whereupon she will connect the party through to a special operator who will complete the call, and the 85 next call will be automatically connected to the operator's set. If a trunk to an idle operator is seized by a line owing to a short, ground, or any other class of "permanent", 90 it is evident that some means must be provided so that the operator can get away from this line to permit the next call to come in. This is done by momentarily depressing the common permanent key which will place an out-of-order tone on the multiple jack sleeve 95 of the "permanent" line and automatically connect the next call to the operator's set. The depressing of the common "permanent" key will also automatically give a signal to the switchboard man that a "permanent" exists and will prevent wrong busy reports on 100 succeeding calls for this line. When the calling party hangs up on an established con-

nection the operator receives standard lamp supervision and both the calling and called party's lines become non-busy in the multiple immediately upon their receivers being released and before the connection is taken down. Both parties can immediately originate new calls, which eliminates the need for any recall features.

The invention is illustrated in the accompanying drawings, in which—

Fig. 1 is a circuit diagram of two manual substations A and A⁰ on the same line, the latter showing the bell and condenser only, a Keith or plunger type line switch C, and a trunk relay group R;

Fig. 2 is a circuit diagram of a trunk finder F, a cord circuit E, a Keith or plunger type line switch C', and party line manual substations A', A², A³, and A⁴;

Fig. 3 is a circuit diagram of a master switch M, a marker distributor S², a marker S', and a set-up control switch S³;

While Fig. 4 is a circuit diagram of an operator's head telephone set and busy test equipment O, together with the necessary keyshelf and metering equipment.

Proceeding now to the detailed explanation of the circuit drawings and referring first to Fig. 1, the manual telephone substations A and A⁰ are connected in bridge of a pair of talking conductors and are arranged for party line ringing currents of different frequencies. As represented herein, substation A comprises essentially the receiver 2, switch-hook 3, transmitter 4, condenser 5, and bell 6. The line conductors 11 and 12 of the substations A and A⁰ terminate at the central office in the individual line switch C and multiple jack J. The line switch C is of the well known Keith or plunger type, modified, however, in circuit arrangement, to be hereinafter explained in detail in connection with its operation. It has access to a plurality of trunk lines extending to trunk relay groups, one of which is shown at R. The trunk relay group R consists essentially of a plurality of relays, together with associated common alarm and tone equipment, and individual signal equipment; also suitable circuits for performing the necessary functions, as will be pointed out hereinafter.

Referring to Fig. 2, the trunk finder F may be briefly described as a rotary line switch whose movable terminals or wipers have no normal position, and which have movement in a forward direction only. In further explanation, it may be stated that the wipers of this switch advance upon the energization of the stepping magnet, rather than upon its de-energization. As shown in the figure, each trunk finder F is associated with a cord circuit, such as E, and has access to a plurality of trunks, each of which extends to a trunk relay group, such as R. The cord circuit E consists essentially of a plurality of relays, a

supervisory lamp L', a plug P', together with associated common ringing generators G', G², G³ and G⁴, to deliver the desired current frequency, and suitable circuits for performing the necessary functions, as will be pointed out hereinafter. The line switch C' is similar to C, in Fig. 1, while the substations A', A², A³, and A⁴ (the latter three having their bell and condenser only shown in bridge of the line) are similar to substation A, Fig. 1, and also have their bells adjusted to respond to different frequency ringing currents.

In Fig. 3 will be found the master switch M which is associated with a group of line switches, such as C, and trunk relay groups, such as R, in Fig. 1, and which functions to step the line switch plungers before an idle trunk immediately after any line switch plunges in on the trunk previously selected. The marker distributor S² advances the wipers 250 and 251 over the banks B³ and B⁴, respectively. The set-up control switch S³ advances the wiper 260 over the bank B⁵. These switches are all similar to the trunk finder F, Fig. 2. There is one marker distributor, such as the switch S², provided for each position. The wiper 251 of switch S² is connected to a starting common which is multiplied through each trunk relay group in the position. Upon each contact in the bank B⁴ is terminated a start conductor which leads to a marker, such as the switch S'. In practice, a number of markers would be provided equal to the maximum number of simultaneous incomplete calls likely to occur in the position. Each marker is associated with a test contact in bank B³, which serves to advance the marker distributor S² when the marker in question is seized. A test conductor from each trunk relay group in the position terminates in the bank B⁴. An operating conductor from each trunk relay group terminates upon a contact in the bank B². The relay 262 of the set-up control switch S³ is connected to a starting common which is multiplied through each marker in the position. A test conductor from each marker is terminated upon a contact in the bank B⁵.

Fig. 4 shows an operator's anti-side tone head telephone set and busy test equipment O, together with the necessary keyshelf and metering equipment, which consists essentially of a plurality of relays, retractive tone equipment, induction coils I and I', jack J², plug P², "no toll" and "call" lamps L² and L³, respectively, "pilot" lamp L⁴, etc., "busy" key K, "permanent" key K', "ring start" keys K², K³, K⁴ and K⁵, permanent and busy peg count meter N, completed call peg count meter N', and suitable circuits for performing the necessary functions, as will be pointed out hereinafter.

Having briefly explained the purpose of the invention and the apparatus involved in carrying it out, the operation of the equipment

may now be explained more in detail. For this purpose it will be assumed that the subscriber at substation A, Fig. 1, desires to obtain connection with the subscriber at substation A', Fig. 2. In order to do this, the subscriber at substation A removes his receiver and when he is cut in to the operator he gives her the number of the desired subscriber.

When the receiver is removed from the switchhook at substation A, line relay 13 of plunger line switch C energizes over a circuit traced from ground at the guard tone equipment, spring 15 and its resting contact, line conductor 12, switchhook 3 and its working contact, receiver 2, transmitter 4, line conductor 11, spring 14 and its resting contact, and relay 13 to grounded battery. Relay 13, upon energizing, closes a circuit for pull-down coil 19 traceable from ground at the guard tone equipment, armature 20 and its working contact, pull-down coil 19, conductor 211, and armature 217 and its resting contact, Fig. 3, to grounded battery. Pull down coil 19, upon energizing, operates both the plunger arm 17 and the cut-off armature 16; the former, through the medium of its plunger (not shown) forces the bank springs 23-26, inclusive, into engagement respectively, with the contacts 27-30, inclusive, and the latter disconnects the line conductors 11 and 12 from the line relay 13 and from ground, respectively. By the engagement of bank springs 23-26, inclusive, with contacts 27-30, inclusive, the line, restricted service, and holding conductors are extended to the trunk relay group R.

By the extension of the line conductors, at bank springs 23 and 26, and contacts 27 and 30, a circuit is closed from ground, lower winding of relay 40, contact 30, spring 26, line conductor 11, transmitter 4, receiver 2, working contact of switchhook 3 and said switchhook, line conductor 12, spring 23, contact 27, and upper winding of relay 40 to grounded battery. Relay 40, upon energizing, places a trunk tone on the calling subscriber's line circuit at armature 46, which will persist until his call is cut in to the operator as will be more fully explained hereinafter. This trunk tone circuit may be traced from the trunk tone apparatus indicated, armature 76 and its resting contact, armature 68 and its resting contact, resting contact of armature 52 and said armature, and working contact of armature 46 and said armature to the subscriber's line circuit. Relay 40 also closes a circuit for the hold-in coil 18 of the line switch C, traceable from ground, hold-in coil 18, spring 24, contact 28, and armature 47 and its working contact to grounded battery. Hold-in coil 18, upon energizing, holds the cut-off armature 16 and plunger arm 17 in operated position after the pull-down coil 19 has deenergized through

the falling back of armature 20 when relay 13 deenergizes—the latter relay being slow acting to make this a positive operation. In multiple with the above traced circuit, a circuit is also completed over the conductor 210 extending to the master switch bank contact upon which the master switch wiper 219 is now resting for energizing the starting relay 215 of the master switch M. Upon energizing, relay 215 closes a circuit for the locking magnet 213, which unlocks the master switch shaft and thus brings about the realignment of all the idle line switch plungers in front of the next idle trunk line. The locking relay 218 also closes a circuit for the open main relay 214, which, upon energizing, disconnects the common conductor 211, at armature 217, from grounded battery in order to prevent any of the line switches from being operated before the master switch comes to rest. The master switch wiper 219 rotates over the bank contacts B in the direction of the arrow in hunting for an idle trunk and has the usual well known solenoid and locking plate equipment to return it from the last to the first contact to permit continuous operation, but since this is well known in the art it will not be explained further.

It will be observed that as soon as the line relay 40 of the trunk relay group R energizes and the circuit is completed for the holding winding 18, battery potential will be placed on the sleeve of conductor, which extends to multiple connected jacks in the positions of the switchboard which have access to the line of station A. This renders the calling line busy to other calling lines as will be explained hereinafter.

A further result of the energization of line relay 40 is the removal of ground, by way of armature 50 and conductor 230, from the contacts associated with the trunk relay group R in the multiple test banks of the markers; and the grounding of the common start conductor 253 leading to the marker distributor S², Fig. 3. For the sake of explanation we may assume that the marker distributor has preselected the marker S' as the next marker to be used; therefore, when relay 40 becomes energized a circuit is closed from ground, armature 62 and its resting contact, armature 57 and its resting contact, armature 51 and its working contact, start conductor 253, wiper 251 of the marked distributor S², first contact in bank B⁴, resting contact of armature 239 and said armature, and line relay 236 to grounded battery. Line relay 236, upon energizing, closes a circuit for switching relay 235 and stepping magnet 234 in series at armature 244, and at armature 243 connects test wiper 232 to the junction of switching relay 235 and stepping magnet 234. The marker S' will now operate in the usual man-

ner to seek an ungrounded contact in the test bank B' . When the ungrounded test contact associated with the trunk relay group R is reached the switching relay 235 will 5 energize and open the circuit of relay 236 at armature 239.

As relay 236 is slow to deenergize a circuit will momentarily be closed from ground, working contact of armature 244 and said 10 armature, working contact of armature 238 and said armature, wiper 232 and the contact upon which it is now standing, marker release trunk conductor 230, armature 50 and its working contact, armature 67 and its resting 15 contact, resting contact controlled by armature 56, armature 49 and its working contact, and relay 42 to grounded battery. Relay 42, upon energizing, closes a locking circuit for itself by placing ground upon 20 marker release trunk conductor 230 by way of armature 62 and its working contact, resting contact controlled by armature 56, resting contact of armature 67 and said armature and working contact of armature 50 and 25 said armature. This ground will maintain switching relay 235 of marker S' energized after relay 236 has deenergized, and will also make the trunk relay group R busy in the multiple test banks of the markers. A 30 further result of the energization of relay 42 is the removal of ground from the starting conductor 253 at armature 62.

A further result of the energization of 35 switching relay 235 is the placing of ground by way of armature 237 upon the contact associated with the marker S' in bank B' of the marker distributor S^2 , whereupon the motor magnet 252 of marker distributor S^2 will operate to advance the marker distributor S^2 into engagement with the next 40 marker. A still further result of the energization of relay 235 is the closure of a circuit from ground, working contact of armature 241 and said armature, conductor 245, 45 through the lamp L^4 , Fig. 4, to battery. Thus it will be seen that a lamp is lighted whenever a marker is taken for use, in order that the operator and supervisor may know 50 how many calls are ahead in waiting.

A still further result of the energization of switching relay 235 is the removal of ground, by way of armature 240, from the contact associated with the marker S' in the bank B' of the set-up control switch S^3 . A 55 still further result of the energization of relay 235 is the closure of a circuit from ground, working contact of armature 242 and said armature, common start conductor 246, through relay 262 of the set-up control switch S^3 to grounded battery. For the purpose of explanation we may assume that the set-up control switch S^3 is at this time in connection with some marker other than the marker S' . The switching relay 264 and start relay 262 are therefore in energized po-

sition, and the placing of additional ground on start conductor 246 of relay 262 is without effect upon line relay 263 because of the open circuit at armature 270. When the marker with which the switch S^3 is in engagement 70 completes its operation the switching relay 264 will deenergize, whereupon a circuit is closed from ground, working contact of armature 266 and said armature, resting contact of armature 270 and said armature, through 75 line relay 263 to grounded battery. Relay 263, upon energizing, will close a circuit for the switching relay 264 and the stepping magnet 261 in series at armature 267, and at armature 268 connects the wiper 260 to the 80 junction of switching relay 264 and stepping magnet 261. The set-up control switch S^3 will now operate in the usual manner to seek an ungrounded contact in the bank B' . When the ungrounded contact associated with the 85 marker S' is reached the switching relay 264 will energize and open the circuit of line relay 263 at armature 270.

As relay 263 is slow to deenergize a circuit will momentarily be closed from ground, 90 working contact of armature 267 and said armature, working contact of armature 269 and said armature, armature 265 and its working contact, wiper 260 and the contact with which it is now engaged, armature 240 95 and its working contact, wiper 233 and the contact with which it is now engaged, conductor 231, resting contact of armature 70 and said armature, Fig. 1, resting contact controlled by armature 54, through relay 43 100 to grounded battery. Relay 43, upon energizing, will close a locking circuit for itself by placing ground upon conductor 231, by way of armature 64 and its working contact. This ground will maintain the switching relay 264 energized after the line relay 263 has 105 deenergized.

A further result of the energization of relay 43 is the operation of switching relay 45 110 by way of armature 65 and its working contact. Relay 45, upon energizing, extends the talking conductors of the calling line to the operator's anti-side tone head telephone set O , Fig. 4, at armatures 73 and 80, by way of conductors 300 and 306, respectively, it being 115 assumed for the sake of explanation that the position is occupied and that the plug P^2 is therefore inserted in the jack J^2 . With the plug P^2 inserted in the jack J^2 it will be observed that a local battery talking circuit is 120 completed which includes ground at the jack J^2 , the transmitter, right hand windings of the induction coil I' , and relay 308. Relay 308, being energized has disconnected battery from armatures 311, 312 and 313, whose function will be explained hereinafter. A further result of the energization of relay 45 is the closing of a circuit for white common 125 call lamp L^3 , at armature 78, by way of conductor 304. This white lamp serves to notify 130

the operator that a trunk is connected to her set. Still a further result of the energization of relay 45 is the disconnection of the trunk tone from the calling subscriber's line, at 5 armature 76, whereby the subscriber knows that his call has been extended to an operator and that she is ready to take his order without waiting for the usual "Number please".

The operator having obtained the desired 10 number, may complete the connection to the multiple jack J' associated with substation A' by the use of any cord circuit, not in use, in her position. For the purpose of explanation we will assume that the operator uses 15 the cord circuit E, Fig. 2, and that she tests the called line in the usual manner by touching the tip of the associated plug to the sleeve of the desired multiple jack. If the called line is found not busy and free from the 20 trouble tone she then inserts the plug P' into the multiple jack J' and depresses momentarily the common frequency selecting key corresponding to the party desired on the line, in this case 33 cycle key K⁴, Fig. 4.

Upon depressing the key K⁴ a circuit is 25 closed which may be traced from ground, holding winding 188 of the line switch C', Fig. 2, sleeve conductors of jack J' and plug P', resting contact of armature 144 and said 30 armature, upper winding of relay 136, resting contact controlled by armature 163, conductor 341, working contact of spring 329 and said spring, conductor 344, and magnet 345 to grounded battery. Magnet 345, upon energizing, 35 operates the peg count meter N' and registers the completed call in the usual well known manner. Holding winding 188, upon energizing, operates the bridge cut-off armature 186 to disconnect the line relay 183 from the line at springs 184 and 185, but 40 has not sufficient power to operate the pull down armature. Relay 136, upon energizing, closes a locking circuit for itself at armature 163, from ground at holding winding 188, 45 as previously traced, and cuts magnet 345, Fig. 4, out of circuit. A further result of the energization of relay 136 is the closing of a circuit for relay 109 of finder switch F at armature 162 traceable from ground, working 50 contact of armature 162 and said armature, armature 140 and its resting contact, resting contact of armature 112 and said armature, and relay 109 to grounded battery. Relay 109 energizes but its function will be 55 explained hereinafter. A still further result of the energization of relay 136 is the closing of a circuit for relay 135 at armature 164 traceable from ground, working contact of armature 164 and said armature, lower 60 winding of relay 135, resting contact of armature 157 and said armature, conductor 341, working contact of spring 329 and said spring, conductor 344, and magnet 345 to grounded battery. Relay 135 energizes only 65 partially over this circuit, it being a so called

two step relay, and armature 158, also marked 1, is the only one attracted at this time. When armature 158 is attracted, however, it closes a locking circuit for relay 135 traceable from ground, working contact of armature 164 70 and said armature, relay 135, working contact of armature 158 and said armature, and working contact of armature 163 and said armature to grounded battery. Relay 135 still will not fully energize as long as the 75 key K⁴ is held depressed since its upper winding, composed of a large number of turns of wire having a relatively high resistance, is shunted out by the circuit including the low resistance winding of magnet 80 345. Upon releasing the key K⁴, however, relay 135 does become fully energized and actuates its armatures marked 2. When armature 157 is actuated the circuit of magnet 345 is opened whereupon said magnet is 85 deenergized.

Returning to a further consideration of the operation of relay 109 of the trunk finder switch F, it may be seen that a circuit is 90 closed for magnet 107 at armature 117 by way of normally grounded bank contact, wiper 105, and armature 114 and its resting contact. Magnet 107 energizes and deenergizes over this and similar circuits, involving the grounded holding bank contacts of unseized 95 trunk relay groups, thus operating to rotate the wipers 104-106, inclusive, until they find the bank contacts to which are connected the line conductors 101 and 103 and the holding conductor 102, now having battery potential 100 thereon, of the seized trunk relay group R. When the wipers reach the contacts, magnet 107 is prevented from operating further, while switching relay 108, heretofore short circuited, will energize and open the circuit 105 of relay 109 at armature 112. As relay 109 is slow to deenergize a circuit will momentarily be closed from ground, working contact of armature 116 and said armature, working contact of armature 113 and said 110 armature, resting contact of armature 137 and said armature, and lower winding of relay 130 to grounded battery. Relay 130 energizes only partially over this circuit, it being a so called two step relay, and its 115 functions will be explained hereinafter.

A further result of the slow releasing of relay 109 is the momentary closing of a circuit from ground, working contact of armature 116 and said armature, working contact of armature 114 and said armature, wiper 105, holding conductor 102, working contact of armature 63 and said armature, and relay 44 to grounded battery. Relay 44, upon energizing, closes a locking circuit for itself at 120 armature 71 by way of armature 48 and its working contact, and opens the circuit of relay 43 at armature 70. Relay 43, upon deenergizing, opens the circuit of relay 45 at 125 armature 65. Relay 45, upon deenergizing, 130

disconnects the operator's head telephone set O, Fig. 4, at armatures 73 and 80; and disconnects the white call lamp L³, Fig. 4, at armature 78. The extinguishing of the lamp L³ indicates to the operator that there are no calls in waiting, while the disconnecting of the operator's head telephone set makes it available for the next incoming call.

A further result of the deenergization of relay 43 is the opening of the circuit of the switching relay 264 of the set-up control switch S³, Fig. 3, at armature 64. Relay 264, upon deenergizing, closes a circuit for relay 263 at armature 270 by way of armature 266 and its working contact. At the same time the circuit of the switching relay 264 is opened at armature 64 the circuit of the switching relay 235 of marker S' is temporarily opened at armature 67, when this armature restores to its normal position, the armature 72 of relay 44 being in its operated or open position at this time. Relay 235, upon deenergizing, opens the circuit of the pilot lamp L⁴, Fig. 4, at armature 241; opens the circuit of relay 262 at armature 242; and places ground on the contact in bank B³ upon which wiper 260 is standing, at armature 240. Relay 262 deenergizes and opens the circuit of magnet 261 at armature 265 before relay 263 energizes and closes a circuit for this magnet at armature 268. From this it will be seen that the set-up control switch S³ becomes dissociated from the marker S' and available for future use.

Returning to a further consideration of the partial operation of relay 130 of the cord circuit E, it may be seen that a locking circuit is closed for the relay at armature 140 traceable from ground, working contact of armature 162 and said armature, armature 140 and its working contact, and relay 130 to grounded battery. Relay 130 does not, however, fully energize at this time due to its top winding being shunted out by a multiple circuit which may be traced from ground, working contact of armature 48 and said armature, Fig. 1, working contact of armature 71 and said armature, working contact of armature 69 and said armature, conductor 102, wiper 105, armature 114 and its working contact, working contact of armature 113 and said armature, resting contact of armature 137 and said armature, and lower winding of relay 130 to grounded battery. A further result of the partial energization of relay 130 is the preparation of a circuit for supervisory lamp L' at armature 138. Still a further result of the partial energization of relay 130 is the closing of the ringing circuit at armatures 141 and 145 which may be traced from ground, working contact of armature 141 and said armature, armature 154 and its resting contact, working contact of armature 161 and said armature, tip conductor of plug P' and jack J', line conductor 181, condenser and

thirty-three cycle bell at substation A', line conductor 182, ring conductor of jack J' and plug P', armature 155 and its resting contact, lower winding of ringing relay 134, working contact of armature 145 and said armature, 70 armature 150 and its resting contact, armature 153 and its resting contact, and thirty-three cycle generator G' to grounded battery. The ringing of the called subscriber's bell now continues until he answers, or the calling subscriber restores his receiver.

When the called subscriber at station A' answers by lifting his receiver from the switch-hook the bell and condenser, which are in bridge of the line, are replaced by the transmitter and receiver in bridge of the line. This permits relay 134 to energize and upon doing so it opens the ringing circuit at armatures 154 and 155, closes the talking conductor through at the latter, and closes a locking circuit for itself at the former which may be traced from ground, working contact of armature 141 and said armature, armature 154 and its working contact, and upper winding of relay 134 to grounded battery. As a further result of the energization of relay 134 a circuit is closed for relay 131 at armature 155 traceable from ground, armature 139 and its resting contact, upper winding of relay 131, working contact of armature 161 and said armature, tip conductors of plug P' and jack J', line conductor 181, receiver and transmitter at substation A', line conductor 182, ring conductors of jack J' and plug P', armature 155 and its working contact, resting contact of armature 143 and said armature, and lower winding of relay 131 to grounded battery. Relay 131, upon energizing, closes a locking circuit for itself at armatures 146 and 147, and closes a holding circuit for the upper winding of relay 136 in series with the hold-in winding 188 of line switch C', at armature 148. Conversation may now take place as desired.

When the calling subscriber restores his receiver to the switchhook the circuit of line relay 40, Fig. 1, will be opened, whereupon the said relay will deenergize and remove battery from the release trunk conductor at armature 47 and the release of the line switch will take place in the usual manner. A further result of the deenergization of relay 40 is the opening of the circuit of relay 44, and the opening of the shunt circuit of the top winding of relay 130, Fig. 2, which also acts as a holding circuit for switching relay 108, at armature 48. Relay 108 deenergizes to restore the finder F to normal, while relay 130 now fully energizes to ground at armature 162, over a circuit previously traced, and actuates its armatures marked 2 whose functions will be explained hereinafter. Relay 44, upon deenergizing, prepares a circuit for the trunk tone at armature 68, places ground on conductor 102 at armature 69, by way of 125

armature 64 and its resting contact, and prepares a circuit for relay 43 at armature 70. A further result of the deenergization of relay 40 is the preparation of the marker release trunk conductor 230 for its normally grounded condition at armature 50. A still further result of the deenergization of relay 40 is the opening of the circuit of relay 42 at armature 49. Relay 42, upon deenergizing places ground on the marker release trunk conductor 230 and prepares ground for the start conductor 253 at armature 62, and prepares several other circuits for future use which need not be specifically pointed out at this time. The trunk relay equipment R is now at normal and may be used to extend other connections.

Returning to a further consideration of the complete operation of relay 130 of the cord circuit E, Fig. 2, it may be seen that a circuit is closed for supervisory lamp L' at armature 139 traceable from ground, armature 139 and its working contact, working contact of armature 156 and said armature, and supervisory lamp L' to grounded battery. The lamp L', upon lighting, notifies the operator of the termination of the conversation. From this it will be observed that the restoration of the receiver at the calling substation causes disconnect supervision to be given the operator whether the receiver at the called substation has been restored or not. In case the calling subscriber abandons the call and hangs up before the called party answers the two-step relay 130 will fully energize and actuate its armatures marked 2 as already described. Armature 142, upon being actuated in such case, closes an energizing circuit for ringing relay 134 whereupon this relay energizes to disconnect ringing current from the called party's line. At the same time the supervisory lamp L' is lighted to notify the operator of the abandonment of the call and permit her to take down the connection.

When the called subscriber restores his receiver the battery feed relay 131 deenergizes in the usual manner, whereupon the shunt around the lower winding of relay 136 is opened at armature 148 and the two windings of this relay are now connected in series with the hold-in winding 188 of line switch C'. The added resistance in relay 136 causes the hold-in winding 188 to release the armature 186, whereupon the springs 184 and 185 are returned to normal and the line switch C' is ready for future use. It will be observed that this is accomplished without the operator taking down the connection. A further result of the added resistance in relay 136 is to prevent the test relay 307, Fig. 4, from energizing when testing the multiple jacks of this line with the tip of another cord circuit.

The operator may now take down the connection by pulling the plug P' from the jack 65 J', whereupon the relay 136 deenergizes and

causes the simultaneous deenergization of relays 135 and 130. Relay 130, upon deenergizing, causes relay 134 to also deenergize, whereby the cord circuit E is returned to normal and available for future use.

An explanation will now be given of the operation should the called line be busy. It will be assumed that the called substation A' is in use when the operator tests the sleeve of the associated multiple jack with the tip of the plug belonging to the cord circuit E. At this time a circuit may be traced from ground, relay 307, conductor 340, resting contact of armature 161 and said armature, tip of plug P', sleeve of multiple jack J', sleeve of multiple jack at another switchboard section, through the relay of the cord circuit which is associated with the last mentioned multiple jack to battery, or to battery at contacts of a relay similar to 40 if the line is busy due to an outgoing call. Relay 307, upon energizing, will close a circuit through the left-hand winding of the operator's induction coil I at armature 310. The current flowing in this circuit will induce a click in the operator's receiver, thus advising her that the called line is busy. The operator will then momentarily depress key K, which causes the busy tone to be placed upon the trunk relay group which at this time is associated with the calling line set up on the storing equipment; causes the next call to be connected to the operator's set, and causes the "permanent and busy call" meter N to operate to register the call.

When the key K is depressed a circuit may be traced from ground, spring 320 and its working contact, conductor 302, working contact of armature 75 and said armature, upper winding of relay 41 to grounded battery. Relay 41, upon energizing, closes a locking circuit for itself at armature 55 by way of ground at armature 48; closes the circuit of the busy tone at armature 52 by way of armature 58; and transfers the holding circuit of relay 43 from ground at armature 64 to ground at key K, Fig. 4. The busy tone persists until the calling subscriber restores his receiver. A further result of the depressing of the key K is the closing of a circuit for relay 346 at spring 321, whereupon relay 346 becomes energized to operate the meter N and register the busy call.

When the operator releases the key K the circuits of relays 346 and 43 are opened at springs 321 and 320, respectively, whereupon they deenergize. Relay 43, upon deenergizing, opens the circuit of relay 45 at armature 65, whereupon relay 45 deenergizes to disconnect the operator's head telephone set O from the relay trunk group R and extinguish the call lamp L², thus notifying her of the disconnection and rendering her set available for future use. A further result of the deenergization of relay 43 is the removal of ground from conductor 231 and the restora-

tion of ground to the conductor 102 at armature 64. The removal of ground from conductor 231 and the temporary removal of ground from conductor 230 at armature 67 causes the call assignor S³ and marker S' to restore to normal and become available for further use, as has already been explained. When the calling subscriber restores his receiver, upon hearing the busy tone, the line relay 40 deenergizes, whereupon battery is removed from the release trunk conductor, the line switch is released, and the circuit of relay 42 is opened so as to become deenergized and perform its functions, all of which have been already explained. A further result of the deenergization of relay 40 is the opening of the busy tone circuit at armature 46; and the opening of the circuit of relay 41 at armature 48, whereupon relay 41 deenergizes to 20 prepare the trunk tone circuit at armature 52, prepare the circuit of relay 43 at armature 54, and place ground upon the contact of bank B' at armature 57 by way of conductor 230 after armatures 50 and 62 have 25 restored to normal position. A still further result of the deenergization of relay 40 is the opening of the circuit of switching relay 235 in series with stepping magnet 234 at armature 50, whereupon relay 235 deenergizes to open the circuit of the pilot lamp L⁴, Fig. 4; open the circuit of relay 262; and place ground on the contact in bank B⁵ upon which wiper 260 is standing, as previously explained.

35 An explanation will now be given of the operation should the calling subscriber's line be a restricted service line. It will be assumed that the calling subscriber A is to be denied certain kinds of service and that he 40 has originated a call and that said call has been extended to an operator's head telephone set O by way of the individual line switch C and preselected relay trunk group R, as already explained. On subscribers' 45 lines having restricted service, a ground is placed on the restricted service bank springs, such as 25, at the individual line switch by means of a juniper wire, such as 31. When the call is cut in to the operator a circuit 50 may be traced from ground, juniper wire 31, bank spring 25, contact 29, armature 79 and its working contact, conductor 305, and red (no toll) lamp L² to grounded battery. The lamp L² will light to notify the operator that 55 the line to which she is connected is a restricted service line. She will then receive the order and either extend the connection by plugging it through or deny the service and so advise the subscriber who will restore his 60 receiver. In either event the circuit including the lamp L² will be broken in the well known manner already explained and the lamp extinguished.

65 An explanation will now be given of the operation should the called subscriber be on

the same line with the calling subscriber. It will be assumed that the subscriber at substation A wishes to converse with the subscriber at A⁰ and that the former has removed his receiver and caused the line switch C to 70 plunge and seize the relay trunk group R. The connection will be extended to the operator as previously explained, whereupon the operator will receive the order and pick up any idle cord circuit, such as E in this case, 75 and make the customary jack sleeve test. When the operator touches the sleeve of jack J with the tip of plug P' a circuit will be closed which may be traced from ground, relay 307, conductor 340, resting contact of 80 armature 161 and said armature, tip of plug P', sleeve of jack J, Fig. 1, bank spring 24, contact 28, and armature 47 and its working contact to grounded battery. Relay 307 will energize over this circuit and close a re- 85 vertive tone circuit which extends from the retractive tone machine by way of armature 309, conductor 301, working contact of armature 74 and said armature, contact 28, spring 24, sleeve of jack J, tip of plug P', armature 161 and its resting contact, conductor 340, condenser 314, and left hand winding of induction coil I to ground. The presence of the tone current in the left-hand winding causes by induction a similar tone in the right- 95 hand winding of the induction coil I which is audible to the operator. The operator upon hearing this tone will connect the calling party to a special operator who will complete the connection and the operator's telephone head set and the storing equipment will become available for other calls in a manner similar to that already explained. Upon termination of the conversation the equipment will restore to normal in the manner already explained.

100 An explanation will now be given of the operation should a trunk to an idle operator be seized by a line having a short, ground or any other class of "permanent" thereon. It 110 will be assumed that a "permanent" exists on the line having the substations A and A⁰ thereon, and that the connection is extended to the operator's telephone head set O, by way of the line switch C and relay trunk group R, in the manner already explained. The operator upon seeing the call lamp lighted, but finding the line unoccupied, realizes a "permanent" exists and momentarily depresses the common "permanent" key K'. 115 When the key K' is depressed a circuit may be traced from ground, spring 322 and its working contact, and magnet 346 to grounded battery. Magnet 346 energizes over this circuit and causes the "permanent and busy call" meter N to operate and register the call. A further result of the depressing of the key K' is 120 the closing of a circuit for relay 41 traceable from ground, spring 323 and its inner working contact, conductor 302, working contact of 125 130

armature 75 and said armature, and upper winding of relay 41 to grounded battery. Relay 41 upon energizing, closes a holding circuit for itself at armature 55 by way of ground at working contact of armature 48 and said armature. A further result of the energization of relay 41 is the transferring of the holding ground for relay 43 from armature 64 to spring 323 at key K', at armature 54, the latter circuit being in multiple with the previously traced operating circuit of relay 41. A further result of the energization of relay 41 is the preparation of a circuit for placing ground on conductor 230 at armature 56, by way of armature 67 and its resting contact, armature 50 and its working contact, after relay 43 has deenergized and relay 44 has energized to actuate its armature 72 as will be explained hereinafter.

At the same time relay 41 is energized, relay 42 is shorted by a circuit traceable from ground, spring 323 of key K', conductor 303, and working contact of armature 77 and said armature, relay 42, closed contacts at armature 49, to ground at the closed contact of armature 62. Relay 42, upon deenergizing, places ground on conductor 102 leading to the private bank of finder F, Fig. 2, and closes a circuit for relay 44 at armature 60. The circuit for relay 44 may be traced from ground, resting contact of armature 60 and said armature, working contact of armature 63 and said armature, and relay 44 to grounded battery. Relay 44, upon energizing, closes locking circuits for itself at armatures 69 and 71 by way of ground at armature 60 and ground at armature 48, respectively, and holds the circuit of relay 42 open at armature 72 to prevent it from energizing before relay 43 deenergizes. A further result of the deenergization of relay 42 is the closing of a circuit for the "permanent" alarm signal at armature 61 by way of ground at the working contact of armature 66 and said armature, which signal persists as long as the operator holds the "permanent" key K' depressed and serves to indicate to the wire-chief the fact that a "permanent" exists on some line. This permanent alarm signal would also serve to indicate to the wire-chief the accidental locking up of relay 43, with no calls having seized the relay trunk group R, which would prevent the subsequent operation of the equipment.

As a result of the joint energization and deenergization of relays 41 and 42, respectively, a trouble tone is connected to the release trunk leading to the sleeve of the multiple jack J at armatures 53 and 59, respectively, traceable from ground at the trouble tone equipment, working contact of armature 53 and said armature, armature 59 and its resting contact, bank contact 28, and spring 24 to the sleeve of the multiple jack J. This tone persists until the trouble is cleared and serves to prevent wrong "busy" reports on succeeding calls for this line. A further result of the joint energization and deenergization of relays 41 and 42, respectively, is the closing of a circuit for the off-normal signal lamp at armatures 57 and 62, respectively, traceable from ground, armature 62 and its resting contact, armature 57 and its working contact, through the off-normal signal lamp to grounded battery. This lamp signal serves to indicate to the wire chief or attendant the particular trunk which is connected to the line upon which the "permanent" exists, so that this line may easily be located.

When the key K' is released the holding circuit of relay 43 is opened at spring 323. Relay 43, upon deenergizing, opens the circuit of relay 45 at armature 65; opens the circuit of the off-normal signal at armature 66; removes ground from conductor 231 leading to the call assigner S³ by way of wiper 233 of marker S' at armature 64; and removes ground from conductor 230 extending to the marker S' at armature 67 while said armature is passing from one contact to the other. From this it will be seen that the operator's telephone head-set O is disconnected from the relay trunk group R, that the marker S' is released while the call assigner S³ is dissociated from the marker S', all of which become available for further use as previously explained.

When the trouble on the line is cleared the line relay 40 deenergizes, whereupon the line switch is released in the manner already explained. A further result of the deenergization of relay 40 is the opening of the circuit of relay 41 at armature 48. Relay 41, upon deenergizing, prepares the trunk tone circuit at armature 52; opens the trouble tone circuit at armature 53; prepares the energizing circuit of relay 43 at armature 54; and opens the circuit of the off-normal signal lamp and places ground on conductor 230 at armature 57. From this it will be seen that the apparatus of the relay trunk group R is restored to normal condition and available for further use.

An explanation will now be given of the operation should there be one or more calls stored up by the storing equipment when a call is originated, or when a call is completed. It will be assumed that the subscriber at A originates a call and that it is received and marked by the marker S', by way of line switch C and trunk relay group R, in the manner already described. Relay 43 of trunk group R, which causes relay 45 to connect the calling subscriber A with the operator, cannot operate until the wiper 260 of the call assigner S³ has reached the contact in the bank B⁵ to which the relay is connected. When wiper 260 reaches this contact relay 43 operates and causes the connection to be extended to the operator who receives the order,

tests the called line, and sets up or denies the connection, as the case may require, whereupon the marker is released and the call assigner dissociated therefrom in the manner already explained. If there are calls in waiting relay 262 will be held energized over the common conductor 246 to cause the call assigner S³ to step its wiper forward, pick up and handle the next call in order regardless of whether the previous call was completed, or connected to busy or trouble tone. Due to the idle markers being preselected in rotation by the marker distributor it will be seen that the marking and storing equipment automatically connects the calls to the operator's talking and listening circuit in the same order as they are originated.

An explanation will now be given of the operation should the called subscriber desire to make a call before the operator has removed the plug from his multiple jack. For the purpose of explanation it will be assumed that a connection has been completed to substation A' by means of the cord circuit E. It will furthermore be assumed that both the calling and called subscribers have restored their receivers, the disconnect lamp L' lighting as previously explained. If the called subscriber should remove his receiver before the operator has removed the plug from the multiple jack, line relay 183 will energize and close a circuit for the pull-in winding, which will in turn energize and cause the line switch C' to plunge and seize a preselected relay trunk group, similar to R, as already explained in connection with line switch C. When the line relay of the relay trunk group energizes, it connects battery to the junction of the hold-in winding 188 and sleeve of the jack J'. Enough current will now flow in the hold-in winding 188 to energize it and hold the line switch in operated position, while a difference of potential will exist at the multiple jacks of the line which is great enough to energize the busy test relay 307 when the operator touches the sleeve of the jack with the tip of the plug.

An explanation will now be given of the operation should the operator fail to properly depress the ringing master key at the time of inserting the plug in the multiple jack of the called line. It will be assumed a call has been cut in to the operator, whose telephone head set is shown at O, and she selects the idle cord circuit E to make the tests and complete the connection to the wanted subscriber A by inserting the plug P' in the jack J. When the plug is inserted in the jack a circuit will be closed which may be traced from ground, left hand winding of induction coil I, condenser 314, conductor 340, resting contact of armature 161 and said armature, tip of plug P' and jack J, and resting contact of spring 15 and said spring to the guard tone equipment as indicated. The presence of the tone

current in the left-hand winding causes by induction a similar tone in the right-hand winding of the induction coil I, which is audible to the operator. The operator upon hearing this tone will properly depress the ringing master key, whereupon relay 136 energizes in series with the cut-off winding of the called line switch and the guard tone circuit is broken.

In order to explain the selective ringing circuits a little more in detail, it will be assumed that the subscriber at substation A² is being called by the subscriber at substation A, for instance, and that the cord circuit E is the one used. The operator inserts the plug P' in the jack J' and since the bell of the called substation A² is adjusted to respond to 50 cycle ringing current she will momentarily depress the corresponding common frequency selecting key K². Upon pressing the key K² a circuit is closed for magnet 345, upper winding of relay 136, and holding winding 188 in series at spring 328, whereupon the peg count meter N' registers the completed call, the relay 136 energizes to perform its functions, and the bridge cut-off armature 186 operates to disconnect the line relay 183 from the line, in the manner already explained. As a further result of the depressing of the key K² a circuit is closed which may be traced from ground, spring 327 and its working contact, conductor 343, working contact of armature 166 and said armature, resting contact of armature 160 and said armature, and relay 132, to grounded battery. Relay 132, upon energizing, closes a locking circuit for itself at armature 149 by way of ground at armature 162. A further result of the energization of relay 132 is the closing of the ringing circuit at armature 150 traceable as previously up to and including the armature 150 but now extending by way of its working contact, armature 152 and its resting contact, and 50 cycle generator G² to grounded battery. This circuit is effective until the called subscriber removes his receiver or the operator breaks the connection by pulling the plug, as already explained. The circuit of relay 132 is opened at armature 162 when relay 136 is deenergized by the operator taking down the connection. Relay 132 is thus restored to normal condition, as is also the other apparatus of the cord circuit E, and the cord circuit is available for further use.

To call the subscriber at A², using the same cord circuit E, the operator will momentarily depress the common frequency selecting key corresponding to the bell on the line, in this case K². Upon depressing the key K² a circuit is closed again for magnet 345, upper winding of relay 136, and holding winding 188 in series at spring 326, whereupon the peg count meter N' registers the completed call, the relay 136 energizes to perform its functions, and the bridge cut-off armature 186

operates to disconnect the line relay 183 from the line, as previously explained. As a further result of the depressing of the key K^2 two circuits are closed simultaneously which 5 may be traced as follows: One circuit may be traced from ground, spring 325 and its working contact, and conductor 343 to grounded battery by way of relay 132 and armatures 160 and 166. Relay 132 energizes 10 and actuates its armatures the same as explained in connection with the depressing of key K^3 . The other circuit may be traced from ground, spring 324 and its working contact, conductor 342, working contact of armature 165 and said armature, resting contact of armature 159 and said armature, and relay 133 to grounded battery. Relay 133, upon energizing, closes a locking circuit for itself at armature 151 by way of ground at armature 162. A further result of the energization of 20 relay 133 is the actuation of armature 152, which together with the actuation of armature 150 of relay 132, closes the ringing circuit traceable as previously up to and including the armature 152 but now extended 25 by way of its working contact, and 66 cycle generator G^4 to grounded battery. This circuit is effective until the called subscriber removes his receiver or the operator breaks 30 the connection by pulling the plug, as already explained. The circuits of relays 132 and 133 are opened at armature 162 when relay 136 is deenergized by the operator taking down the connection. Relays 132 and 133 35 are thus restored to normal condition, as is also the other apparatus of the cord circuit E, and the cord circuit is available for further use.

To call the subscriber at A^4 , again using the 40 same cord circuit E, the operator will momentarily depress the common frequency selecting key corresponding to the bell on the line, in this case K^5 . Upon depressing the key K^5 a circuit is closed as usual for magnet 45 345, upper winding of relay 136, and holding winding 188 in series at spring 331, whereupon the peg count meter N' registers the completed call, the relay 136 energizes to perform its functions, and the bridge cut-off armature 186 operates to disconnect the line relay 183 from the line, as previously explained. As a further result of the depressing of the 50 key K^5 a circuit is closed which may be traced from ground, spring 330 and its working contact, and conductor 342 to grounded battery by way of relay 133 and armatures 159 and 165. Relay 133 energizes and actuates its armatures the same as explained in connection 55 with the depressing of key K^2 , only armature 150 is not actuated at this time and armature 153 closes the ringing circuit traceable as previously up to and including this armature but now extended by way of its working contact, and 66 cycle generator G^2 to grounded bat-

tery. This circuit is effective until the called 65 subscriber removes his receiver or the operator breaks the connection by pulling the plug, as already explained. Relay 133, as well as the other apparatus of the cord circuit E, is restored to normal condition when 70 the operator takes down the connection and the cord circuit is available for further use, as has also been previously explained.

It should be noted, in considering the ringing circuits, that the provision of the two step 75 relay 135 is what makes it possible to use the common ringing current selecting keys K^2 , K^3 , etc. rather than keys individual to each cord circuit. When any ringing key such as 80 K^2 is depressed relay 135 operates in its first step along with relay 136, and when such key is released relay 135 operates in its second step. On completely operating, relay 135 opens the initial energizing circuits of selecting relays 132 and 133 at armatures 159 and 85 160, thereby preventing any false operation when a key is later operated to control the ringing current selection at another cord circuit.

An explanation will now be given of the operation should the operator, using the telephone head set O, Fig. 4, vacate her position. When she removes the plug P^2 from the jack J^2 the circuit including the operator's transmitter, the right-hand windings of the induction coil I' and the relay 308 is broken. Relay 308, upon deenergizing, releases the armatures 311, 312 and 313, whereupon battery potential is placed on the contacts of master-switch bank B^0 corresponding to all relay 100 trunk groups, such as R , assigned to that particular operator's position. It will be seen that armatures 311 and 312 are connected to contacts in bank B^0 of master-switch M, by way of conductors 209 and 204, respectively, 105 while armature 313 is connected to a contact in another master switch bank; also it will be understood that there may be other armatures similarly connected. Should the master switch wiper 220 now be rotated to the contact in bank B^0 , to which the conductor 209 is connected, a circuit is closed traceable from ground, lower winding of relay 215, wiper 220, conductor 209, and working contact of armature 311 and said armature to grounded battery. Relay 215 will energize over this 110 circuit and cause the master switch M to immediately rotate to the next contact, or until one is found not having battery potential thereon, in the manner already explained. 115 From this it will be seen that an operator can leave her position and busy it to all incoming calls by merely removing her telephone head-set plug from the jack.

Having described my invention, what I 125 consider to be new and desire to have protected by Letters Patent will be pointed out in the appended claims.

What is claimed is:

1. In a call distributing system, trunk circuits, automatic switches responsive to the initiation of calls for extending the calling lines to idle trunk circuits, an operator's switchboard, and means including sorting devices for connecting trunk circuits upon which calls are waiting to the operator's head set in the exact order in which such trunk 10 circuits are connected with.
2. In a call distributing system, trunk circuits, automatic switches responsive to the initiation of calls for extending the calling lines to idle trunk circuits, an operator's switchboard, means including sorting devices for connecting trunk circuits upon which calls are waiting to the operator's head set in the exact order in which such trunk circuits are connected with, and a visual signal at said 20 switchboard operated automatically when any trunk circuit is connected to said head set.
3. In a call distributing system, trunk circuits, automatic switches responsive to the initiation of calls for extending the calling lines to idle trunk circuits, an operator's switchboard, means including sorting devices for connecting trunk circuits upon which calls are waiting to the operator's head set in the exact order in which such trunk circuits are 30 connected with, and means including a bank of signals at said switchboard for indicating the number of waiting calls.
4. In a telephone exchange system, a plurality of subscribers' lines, a plurality of trunks, means whereby any one of said lines can be automatically connected to an idle one of said trunks upon a call being originated, means effective responsive to the operation of the first named means for automatically extending said trunk to an idle operator, means including an automatic switch whereby the operator can complete the connection to the called subscriber's line, and means whereby the called party can 40 originate a call to an idle operator immediately after he and the calling party have hung up and before the previous connection is taken down.
5. In a telephone exchange system, a plurality of line switch and jack ending subscribers' lines, a plurality of trunks, means whereby any one of said lines can be automatically connected to an idle one of said trunks upon a call being originated, means effective responsive to the operation of the first named means for automatically extending said trunk to an idle operator, means whereby the operator can complete the connection, and means whereby the sleeves of 50 both the calling and called party's multiple jacks will test non-busy to calls for those lines immediately after the calling and called parties have hung up and before the connection has been taken down.
6. In a telephone system, means including an automatic switch and a cord circuit for connecting a calling and a called line, means including a key for placing a test potential upon the sleeves of the jacks associated with the connected called line, means controlled 65 by the calling subscriber for releasing said switch, and means under the joint control of the calling and called subscribers for removing said busy potential while the cord circuit remains connected to the called line. 70
7. In a telephone system, means including an automatic switch and a cord circuit individual to said switch for connecting a calling and a called line, a cut-off relay for the called line energized over the sleeve of said cord, means responsive to the hanging up 75 of the receiver by the calling subscriber for releasing said switch, and means responsive to the hanging up of the receivers by both subscribers for deenergizing said relay. 80
8. In a telephone system, means including an automatic switch and a cord circuit for connecting a calling and a called line, a cut-off relay for the called line energized over the sleeve of said cord, means responsive to the hanging up of the receiver by the calling party for releasing said switch, and means responsive to the hanging up of the receivers by both subscribers for deenergizing 85 said relay, said last means comprising 90 circuit arrangements in the said cord circuit for inserting a resistance in the sleeve circuit thereof to cause said cut-off relay to deenergize as set forth.
9. In a telephone system, means including a cord circuit for connecting a calling and a called line, a cut-off relay for the called line and a sleeve relay in said cord circuit energized in series, said sleeve relay having two windings one of which is normally short circuited, and means responsive to the replacement 100 of the receiver at both calling and called stations for removing said short circuit, thereby increasing the resistance of the sleeve circuit sufficiently to deenergize said 105 cut-off relay.
10. In a call distributing system, trunk circuits, cord circuits, means responsive to the initiation of a call for connecting the calling line to an idle trunk circuit at one end thereof, and means responsive to the act of ringing the called party after one of said 110 cord circuits has been plugged into the called line for connecting the cord circuit in use with the connected trunk circuit at the other end thereof. 115
11. In a call distributing system, trunk circuits, cord circuits, means responsive to the initiation of a call for connecting the calling line to an idle trunk circuit at one end thereof, finder switches individual to said 120 cord circuits, respectively, and operator controlled means effective only after one of said 125

- cord circuits has been plugged into the called line for starting the associated finder in search of the trunk circuit to which the calling line is connected.
- 5 12. In a call distributing system, trunk circuits, line switches responsive to calls for connecting calling lines to said trunk circuits, cord circuits for completing connections to called lines, and finder switches individual to the cord circuits for connecting them with said trunk circuits. 75
13. In a call distributing system, trunk circuits, line switches responsive to calls for connecting calling lines to said trunk circuits, cord circuits for completing connections to called lines, finder switches individual to said cord circuits, and means for causing the finder associated with any cord circuit in use to connect such cord circuit with 80 the particular trunk circuit to which the calling line is connected.
14. In a call distributing system, trunk circuits, automatic switches for extending calling lines to said trunk circuits, means for extending connected trunk circuits to the operator one at a time, multiple jacks associated with said lines, and operator controlled means in each trunk circuit for placing a distinctive tone on the sleeves of the multiple jacks associated with the connected line. 90
15. In a call distributing system, trunk circuits, automatic switches for extending calling lines to said trunk circuits, means for extending connected trunk circuits to the operator one at a time, multiple jacks associated with said lines, a trouble tone relay in each trunk circuit for placing a distinctive tone on the multiple jacks of any connected line, and circuits over which the operator controls 95 said relays.
16. In a call distributing system, means including an automatic switch for extending a calling line to an operator, multiple jacks associated with the calling line, a cord circuit for use in testing the called line and for extending the connection thereto, a test relay associated with the operator's head set, a circuit for said relay including the tip of said cord, means controlled by said relay for placing a distinctive tone on the multiple jacks of the calling line through contacts of said switch, and an inductive connection between the circuit of said test relay and the operator's head set circuit, whereby in case the called line is 100 the same as the calling line the operator will hear said tone when she touches one of said jacks with the tip of said cord.
17. In a telephone exchange system, a plurality of line switch and jack ending subscribers' lines, a plurality of relay trunk groups, means whereby any one of said lines can be automatically connected to an idle one of said trunks upon a call being originated, means for automatically extending said trunk to an idle operator, a plurality of plug and finder 105
- switch ending cord circuits whereby the operator can set up the connection by inserting the plug of any one of said cords in the jack of the wanted line, a plurality of ringing keys, a guard tone machine, and means whereby the operator instantly receives a guard tone from said machine upon failure to properly depress one of said keys at the time of inserting said plug in the multiple jack of the called line. 110
18. In a telephone system, cord circuits for use in connecting calling and called lines, ringing current selection control keys, and means for audibly signaling the operator in case she plugs one of said cord circuits into a called line without having first operated one of said keys. 115
19. In a telephone system, cord circuits for use in connecting calling and called lines, ringing current selection control keys, ringing current selecting relays in each cord circuit controlled by said keys, and means for signalling the operator in case she plugs one of said cord circuits into a called line without having first set said selecting relays by operating one of said keys. 120
20. In a cord circuit, a ringing current selecting relay, a sleeve relay energized when the cord is connected to a called line, ringing current selection control keys, a relay in said cord operated responsive to the actuation and restoration of one of said keys, and a circuit for said selecting relay controlled jointly by the other of said relays. 125
21. In a cord circuit, a ringing current selecting relay, a sleeve relay energized when the cord is connected to a called line, ringing current selection control keys, a relay in said cord operated responsive to the actuation and restoration of one of said keys, a circuit for said selecting relay including normally open contacts on said sleeve relay and normally closed contacts on said last mentioned relay. 130
22. In a telephone system, a plurality of cord circuits, ringing current selecting relays in each cord circuit, ringing current selection control keys common to said cord circuits, circuits whereby said keys control the selecting relays in all said cord circuits, and means in each cord circuit in use for removing the associated selecting relays from the control of said keys responsive to the restoration of an operated one of said keys. 135
23. In a telephone system, a cord circuit for connecting with a called line, a cut off relay for said line, a sleeve relay in said cord, a ringing key, and an initial energizing circuit for both said relays in series closed by the actuation of said key. 140
24. In a telephone system, a cord circuit for connecting with a called line, a cut off relay for said line, a sleeve relay in said cord, ringing current selecting means in said cord, keys for controlling said means, and 145

- an energizing circuit for said relays also controlled by said keys.
25. In combination, a cord circuit, an operator's head set, a normally closed test circuit extending to said head set from the tip of said cord, a relay for opening said test circuit, a ringing key, and a circuit for said relay closed by the actuation of said key.
26. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, and a supervisory signal controlled by said relay.
27. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, and a circuit for signalling the called line controlled by said relay.
28. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, a circuit for signalling the called line controlled by said relay, a ring cut off relay, and a locking circuit for said ring cut off relay also controlled by said two step relay.
29. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, a signalling circuit, a ring cut off relay, and an initial energizing circuit for said ring cut-off relay controlled by said two step relay in the second stage of its operation.
30. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, a signalling circuit, a ring cut-off relay, a locking circuit for said ring cut-off relay controlled by said two step relay in the first stage of its operation, and an initial energizing circuit for said ring cut off relay controlled by said two step relay in the second stage of its operation.
31. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, a double wound sleeve relay in said cord circuit energized in series with the cut off relay of the called line, and a shunt for one winding of said sleeve relay controlled by said two step relay.
32. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, a double wound sleeve relay in said cord circuit energized in series with the cut-off relay of the called line, a battery feed relay in bridge of the cord, contact on said two step relay included in said bridge, and a shunt for one winding of said sleeve relay controlled jointly by said two step relay and said battery feed relay.
33. In a telephone system, a cord circuit for use in connecting a calling and called line, a two step relay in said cord circuit operated in its first stage responsive to the connection of said cord circuit with the calling line, circuit arrangements for operating said relay in its second stage responsive to the replacement of the receiver at the calling station, a sleeve relay energized in series with the cut-off relay of the called line, a battery feed relay in bridge of said cord circuit, and means jointly controlled by said two step relay and said battery feed relay for increasing the resistance of the sleeve circuit to deenergize said cut-off relay while the sleeve relay is maintained energized.
34. In a cord circuit, a double wound relay, a connection from one talking strand of the cord to one pole of the exchange battery including one winding of said relay and a pair of contacts operated by the relay armature, and a connection from the other talking strand of the cord to the other pole of said battery including the other winding of said relay and another pair of contacts operated by the relay armature.
35. In a cord circuit for use in connecting a calling and called line, a relay, a second relay connected in bridge of the talking strands at the called end of the cord in series with a battery, the connection including contacts of said first relay, contacts on said second relay for shunting the said contacts on said first relay when the second relay is energized over

the called line, and means responsive to the replacement of the receiver at the calling station for energizing said first relay to open its said contacts.

- 5 36. In a telephone exchange system, a plurality of lineswitch and jack ending subscribers' lines, the jacks of said lines having two talking terminals and a sleeve terminal, a plurality of trunks, means for automatically operating the lineswitch associated with a calling line to connect said line to an idle one of said trunks, operator controlled means for completing the connection, and means whereby the sleeve terminals of both calling and 15 called parties multiple jacks will test non-busy to calls for those lines immediately after the calling and called parties have hung up their receivers and before the connection has been taken down.
- 20 37. In combination, a cord circuit, an operator's head set, a test circuit extending to said head set from the tip of said cord, a ringing key, a relay for opening said circuit operative responsive to the actuation of said key, 25 said circuit including normally closed contacts on said relay, and a locking circuit for said relay.

- 30 38. In combination, a cord circuit, an operator's head set, a test circuit extending to said head set from the tip of said cord, a ringing key, means controlled by said key for opening said test circuit and for completing a link in the talking circuit, and means for maintaining said first means operated independent of said key.

- 35 39. In a call distributing system, trunk lines, means including an automatic switch for connecting a calling line to a trunk line, an operator's circuit, means for extending the 40 connected trunk line to said circuit, and operator controlled means for disconnecting the connected trunk line from said circuit and for locking said automatic switch in position.

- 45 40. In a call distributing system, trunk lines, means including an automatic switch for connecting a calling line to a trunk line, an operator's circuit, means for extending the connected trunk line to said circuit, operator controlled means for disconnecting the connected trunk line from said circuit and for locking said automatic switch in position, and a signal operated responsive to said automatic switch being locked.

- 50 41. In a telephone system, a plurality of subscribers' lines, a trunk circuit, means effective responsive to the removal of the receiver at a subscriber's station terminating a line to connect one end of the trunk to that line, a plurality of plug ending cord circuits, 55 automatic switching mechanism effective responsive to the insertion of the plug of any cord into a jack for connecting the other end of the trunk to said cord.

- 60 42. In a telephone system, a plurality of subscribers' lines, a plurality of cord circuits,

a plurality of trunk circuits, each trunk for connecting any line with any cord, a signal, means responsive to the removal of the receiver at a subscriber's station terminating a line to connect that line to an idle trunk and 70 to operate said signal, and means effective responsive to the taking of any cord into use to connect said cord with the selected trunk and to release said signal.

75 43. In a telephone system, a plurality of trunks, an operator's head set, automatic selecting mechanism effective responsive to the taking of a trunk into use to connect said operator's set to the trunk, a plurality of cord circuits and means effective responsive to the operator taking any cord circuit into use for connecting the cord to the trunk to which the operator's set is connected and disconnecting the head set.

80 44. In a telephone system, a plurality of trunks, an operator's head set, automatic selecting mechanism having a receiving position for each of said trunks adapted under predetermined conditions to connect said operator's set to any trunk, a plurality of cord 90 circuits, and means effective responsive to the operator taking any cord circuit into use for connecting the cord to the trunk to which the operator's head set is connected and disconnecting the head set.

95 45. In a telephone system, a group of trunks, means for seizing idle trunks of the group in a certain order, an operator's head set, automatic selecting mechanism having a receiving position for each 100 of said trunks adapted to successively cause the connection of said operator's set to certain seized trunks in the same order as the trunks are seized, said connection excluding the said receiving position of the trunk in 105 the selecting mechanism, means effective responsive to the connection of the operator's headset to one of the trunks to stop the further operation of the mechanism, and means under the control of the operator for disconnecting the headset from the trunk to 110 which it is connected and reinitiating said automatic selecting mechanism into operation.

115 46. In a telephone system, a group of trunks, means for seizing idle trunks of the group in a certain order, an operator's head set, automatic selecting mechanism having a receiving position for each of said trunks adapted to successively connect said operator's set to seized trunks in the same order as the trunks are seized, means effective responsive to the connection of the operator's set to one of the trunks to stop the further 120 operation of the mechanism, a plurality of cord circuits, means automatically effective responsive to the operator taking any cord circuit into use for connecting the cord to the trunk to which the operator's head set 125 is connected, disconnecting the head set from 130

the trunk, and for preventing the connection of the headset to that trunk while the trunk is in use.

47. In a telephone system, a plurality of lines terminating in jacks, a plug ending cord for connecting a calling line to a called line, means effective when the plug of a cord is inserted into the jack of a called line to render the called line busy, means in each cord initiated in its operation when a connection is established from a calling line to the cord and fully operated when the call is terminated by the calling party to render the called line idle under predetermined conditions regardless of the presence of the plug in the jack of the line.

48. In combination, a cord circuit, a ringing key, and a relay individual to said cord

circuit energized over a circuit including a contact on the key in series with the sleeve 20 of the cord.

49. In a telephone system, a plurality of cord circuits, an operator's head set, a test circuit extending to said head set, said circuit including a plurality of branches each 25 of which is normally connected to one of said cord circuits, and a relay in each cord circuit for opening the associated branch, a ringing key, and a circuit for operating any unoperated relay of any cord over which a 30 call has been extended, said circuit being effective responsive to the operation of the key.

In witness whereof, I hereunto subscribe my name.

JOHN E. OSTLINE.
